COLLAPSIBLE BOX

Arthur L. Whiton, Evanston, Ill., assignor to
 Chicago Mill and Lumber Company, Chicago,
 Ill., a corporation of Delaware

Application December 7, 1934, Serial No. 756,393

6 Claims. (Cl. 217—12)

This invention relates to an improved type of collapsible box or crate, and more particularly to a box wherein the various walls are provided with either grooved cleats or battens, with said cleats and battens interfitting one another to lockingly hold the various walls of the box in interfitting relation with one another, with the last wall when in closed position serving as a lock for certain of the other walls of the box.

10. It is an object of this invention to provide a collapsible box or crate, the walls of which are locked together by means of interfitting grooved cleats and battens.

It is also an object of this invention to provide 15 a collapsible box wherein the various walls are interfittingly engaged with one another without the use of metal guides and the like.

It is a further object of this invention to provide a knock-down box or crate wherein the various walls are provided with grooved interfitting cleats and battens formed with tenons and mortises facilitating the interlocking of the various walls of the box or crate, with the last wall insertable in position adapted to be provided with a locking or securing means which serves to hold 20 the box or crate assembled and prevents opening and separation of the interfitting walls of the box or crate.

25. It is furthermore an object of this invention to provide a collapsible or knock-down box or crate consisting of a plurality of walls or panels constructed of wood and having wooden grooved cleats and battens secured thereto, allowing the walls to be slidably interfitting with one another 30 in a predetermined order, with certain of the walls locking other of the walls in place and with the final wall being provided with locking means to act as a locking means to serve as a lock to prevent dismantling of the box or crate.

35. It is an important object of this invention to provide an all-wood collapsible box or crate, the various walls of which are provided with dovetailed tenons and mortises permitting each of the walls to be slidably interfitting with two of the other box walls to permit rapid assembly and dismantling of the box and requiring a securing means for only the last wall insertable in position 40 for locking or closing the entire box in its assembled form.

45. Other and further important objects of this invention will be apparent from the disclosures in the specification and the accompanying drawings.

50. The invention (in its preferred form) is illus-

trated in the drawings and hereinafter more fully described.

On the drawings:

Figure 1 is an isometric view of a collapsible or knock-down box or crate embodying the principles of this invention and showing the slideable interfitting relation of the box walls incompletely assembled. 5

Figure 2 is an end elevation of the collapsible box in complete assemblage with the top locking means in position. 10

Figure 3 is a fragmentary isometric view of one of the battens or cleats removed from a box wall. 15

Figure 4 is an enlarged top plan view of the completely assembled box or crate showing the top wall locking means in position.

Figure 5 is a fragmentary vertical detail section taken on line V—V of Figure 4.

Figure 6 is a fragmentary vertical detail section taken on line VI—VI of Figure 4.

Figure 7 is a fragmentary detail section taken on line VII—VII of Figure 2.

As shown on the drawings:

The improved collapsible or knock-down box 25 is constructed entirely of wood, with the possible exception of nails, glue or other securing means securing the cleats and battens to the walls of the box, as hereinafter more fully described. The knock-down box comprises two end walls or panels 30 each of which has rigidly secured across the bottom margin of the outer face thereof a bottom cleat 2. Also rigidly secured to the outer surface of each of the end walls 1 are a pair of parallel battens 3 the lower ends of which seat upon 35 the upper surface of the bottom cleat 2. The end wall battens 3 extend upwardly to within a short distance of the upper end of the end wall and each of said battens 3 is provided with a V-shaped groove or half dovetail mortise 4 forming a half 40 dovetail tenon 5 on the batten.

Rigidly secured across the bottom margin of the inner face of each of the end walls or panels 1 is a bottom cleat 6 which is also provided with a V-shaped or half dovetail mortise 4 and with a 45 half dovetail tenon 5. Also rigidly secured on the inner surface of each of the end walls 1 across the upper margin thereof is an upper cleat 7 which is also provided with a half dovetail mortise 4 and with a half dovetail tenon 5. An opening 8 is provided through the top central portion of each of the end walls or panels 1 and extends through each of the upper cleats 7.

Removably disposed between the bottom ends of the end walls 1 is a slideable bottom wall or panel 55

9 which is also constructed of wood and has rigidly secured to the bottom side thereof a pair of transversely disposed parallel battens 10. Each of the battens 10 is provided with a V-shaped or half dovetail mortise 4 and with a half dovetail tenon 5. As clearly illustrated in Figure 1, the bottom wall 9 is slidably pushed into position with the bottom battens 10 slidably interfitting the bottom end wall cleats 6. The width of the bottom wall 9 is exactly the same as the width of the end walls 1, and the length of the battens 10 is exactly the same as the length of the bottom end wall cleats 6.

The opposite sides of the collapsible box or crate are closed by means of removable side walls or panels 11, each of which has rigidly secured across the end margins of the inner sides thereof a pair of parallel cleats 12, each of which is provided with a half dovetail mortise 4 and with a half dovetail tenon 5. As clearly illustrated in Figures 1 and 2, the width of the side walls 11 is slightly greater than the length of the side wall cleats 12 and project beyond the lower ends of the side wall cleats to form an overlapping retaining bead or flange at 13 substantially equal to the thickness of the bottom wall 9 to seat adjacent the side edges of said bottom wall to hold the same locked in position when the side walls are in their lowermost position with the side wall cleats slidably interfitting the end wall battens 3 and with the lower ends of the side wall cleats seating against the top of the end wall bottom cleats 2.

The box is now completely assembled with the exception of the top which is removable and consists of a top wall or panel 14 having rigidly secured transversely upon the top surface thereof a pair of parallel top wall battens 15 each of which is formed with a half dovetail mortise 4 and with a half dovetail tenon 5. The top wall 14 is slidably pushed into position with the end margins of the wall slidably engaged beneath the top end wall cleats 7 and with the top wall battens 15 slidably interfitting the top end wall cleats 7. When the top wall is in its completely closed position, the side or longitudinal margins of the top wall 14 overlap the upper edges of the side walls 11, as clearly illustrated in Figure 6, thereby locking the side walls against slidable upward movement and completing the assembly of the knock-down box or crate.

Any suitable means may be employed for the purpose of securing the top wall 14 in place against removal so that the box may be used for shipping purposes and the like. One means for locking the top wall in position is by the use of a spring cotter pin 16 which is slidably projected through an opening 17 (Figure 1) which extends transversely through each of the top wall battens 15. When the top wall is in its closed position the openings 17 register with the openings 8 in top margins of the end walls of the box so that the split ends of the cotter pins can project through the slots 17 and have their ends bent over as clearly illustrated in Figures 2 and 4. If desired, the top wall 14 may be nailed to the side walls 11 or any other satisfactory means may be employed for securing the top wall in place to complete the locking up of the box.

The improved collapsible box or crate has the various walls thereof provided with grooved cleats or battens which are so arranged that the various walls may be slidably interfitted with one another with the side walls serving as a locking means for locking the bottom wall and end walls in place and with the top wall serving as a locking means

for locking the two side walls against removal. The box may be readily disassembled when not in use to permit reshipment and reuse thereof. The interfitting and interlocking arrangement of the various walls of the collapsible box provides an arrangement which eliminates the necessity of providing nails, screws or other devices for fastening the walls together to form a completed container requiring only a locking means for securing the top wall in place to prevent disassembly of the box. A novel result is accomplished by the use of the cleats and battens which are each provided with a half dovetail mortise and a half dovetail tenon permitting the slidable interfitting and interlocking of the various walls of the box.

It will, of course, be understood that various features of this construction may be varied through a wide range without departing from the principles of this invention, and it is, therefore, not the purpose to limit the patent granted hereon otherwise than necessitated by the scope of the appended claims.

I claim as my invention:

1. A collapsible box comprising a pair of end walls having dovetailed cleats and battens secured thereto, a bottom wall having dovetailed battens secured thereto slidably interfitting certain of the dovetailed cleats of the end walls, a pair of side walls having dovetailed cleats secured thereto and slidably interfitting the dovetailed battens of the end walls, said side walls when in position overlapping the side edges of the bottom wall to hold the bottom wall locked in position, and a top wall having dovetailed battens secured thereto and slidably interfitting the dovetailed cleats of the end walls, said top wall when in position overlapping the upper edges of the side walls to hold the side walls locked in place.

2. A collapsible box comprising a pair of end walls having dovetailed cleats and battens secured thereto, a bottom wall having dovetailed battens secured thereto slidably interfitting certain of the dovetailed cleats of the end walls, a pair of side walls having dovetailed cleats secured thereto and slidably interfitting the dovetailed battens of the end walls, said side walls when in position overlapping the side edges of the bottom wall to hold the bottom wall locked in position, a top wall having dovetailed battens secured thereto and slidably interfitting the dovetailed cleats of the end walls, said top wall when in position overlapping the upper edges of the side walls to hold the side walls locked in place, and means for locking the top wall in position to lock the assembled box.

3. A collapsible box or crate comprising in combination a plurality of dovetailed members secured to the walls and slidably interfitting one another to hold all of the walls in slidable assembled relation, and means for releasably securing one of the walls in position to lock the remaining walls against slidable disengagement from one another.

4. A collapsible box comprising a pair of end walls, stop cleats secured to the outer surfaces thereof, dovetailed battens also secured to the outer surfaces of the end walls, lower dovetailed cleats and upper dovetailed cleats secured to the inner sides of the end walls, a bottom wall, dovetailed battens secured to the bottom surface thereof and slidably engaged with the bottom dovetailed cleats of the end walls, a pair of side walls, dovetailed cleats secured to the inner sur-

faces thereof and slidably interfitting the dovetailed battens on the outer surfaces of the end walls, said side walls overlapping the side edges of the bottom wall to hold the bottom wall in position against removal, a top wall, and dovetailed battens secured to the top surface of the top wall and slidably interfitting the upper dovetailed cleats of the end walls to hold the entire box in assembled relation, said top wall when in position overlapping the upper edges of the side walls to hold the same locked against removal.

5. A collapsible box comprising a pair of end walls, stop cleats secured to the outer surfaces thereof, dovetailed battens also secured to the outer surfaces of the end walls, lower dovetailed cleats and upper dovetailed cleats secured to the inner sides of the end walls, a bottom wall, dovetailed battens secured to the bottom surface thereof and slidably engaged with the bottom dovetailed cleats of the end walls, a pair 10 of side walls, dovetailed cleats secured to the inner surfaces thereof and slidably interfitting

the dovetailed battens on the outer surfaces of the end walls, said side walls overlapping the side edges of the bottom wall to hold the bottom wall in position against removal, a top wall, dovetailed battens secured to the top surface of the top wall and slidably interfitting the upper dovetailed cleats of the end walls to hold the entire box in assembled relation, said top wall when in position overlapping the upper edges of the side walls to hold the same locked against removal, 15 and means for securing the top wall to the body of the box to completely lock the entire box and prevent disassemblage thereof.

6. A collapsible box of the class described comprising top, bottom, sides and end walls, and 20 mortised and tenoned members secured to said walls positioned to enable all of said walls to be slidably interengaged with one another in a pre-determined order to lock the bottom wall and the side walls from disengagement with the end walls when the top wall is in closed position.

ARTHUR L. WHITON.
